UNITED STATES PATENT OFFICE.

JOHN WHEELER, OF CRIPPLE CREEK, COLORADO.

GAGE.

1,151,141.

Specification of Letters Patent. Patented Aug. 24, 1915.

Application filed March 6, 1915. Serial No. 12,585.

To all whom it may concern:

Be it known that I, JOHN WHEELER, a citizen of the United States, residing at Cripple Creek, in the county of Teller and 5 State of Colorado, have invented certain new and useful Improvements in Gages, of which the following is a specification, reference being had to the accompanying drawings.

10 My present invention relates broadly to new and useful improvements in gages of the type in which a marker bar is provided for use in marking on the board or other element to be cut, the desired sawing line.

15 More specifically, my invention pertains to an improved form of siding gage which is adapted to be used in marking the length to which a piece of siding about to be applied to a building, shall be cut.

20 The principal object of my present invention is to provide a siding gage which consists in three pivotally united sections, one of which serves as a means whereby the gage may be secured in supporting position 25 against the wall of the building, the second of which is adapted to be used as a marker bar when the sawing line is being made upon the weather-board or piece of siding and the third of which is employed in determining the position of the weather-board or 30 piece of siding which is about to be applied.

Another object and one of equal importance with the foregoing, is to so construct the device that the joint between the marker 35 bar and gage bar constitutes a supporting lug for the new strip of weather-board which is being nailed to the building.

The above and additional objects are accomplished by such means as are illustrated 40 in the accompanying drawings, described in the following specification, and then more particularly pointed out in the claims which are appended hereto and form a part of this application.

45 With reference to the drawings, wherein there has been illustrated the preferred embodiment of this invention, as it is reduced to practice, and throughout the several views of which similar reference characters designate corresponding parts, Figure 1 is a vertical section taken through a building wall and showing the improved device in use thereon, Fig. 2 is a perspective view of the hanger bar, Fig. 3 is a perspective view of

the marker bar, Fig. 4 is a perspective view 55 of the gage bar, and Fig. 5 is a perspective view of the knife slide.

As shown best in Fig. 1 of the accompanying drawings, my invention in its preferred embodiment, consists essentially of a hanger 60 bar 10, a marker bar 11, and a gage bar 12. The hanger bar 10 is, as are the other elements of the device, preferably formed of steel or some similar metal and is arcuate in conformation adjacent its lower terminal. 65 The upper terminal portion 13 of the member 10 is substantially straight and is provided with a straight flat face indicated at 14. This flat face 14 is adapted to engage against the piece of studding or siding to 70 which the hanger bar is applied and is secured thereto by a barb or spike indicated at 15. It will be readily apparent, particularly upon reference to Fig. 1, that the lower arcuate portion of the hanger bar is spaced 75 a considerable distance from the wall, when the upper portion 13 has been properly secured.

The extreme lower terminal of the member 10 is provided with a pair of spaced 80 apertured hinge ears 16, between which is pivotally secured on a pin or axle 17, an apertured lug 18 which extends longitudinally from the upper terminal of the marker bar 11. This marker bar 11 is in cross section substantially T-shaped, the purpose in thus forming the marker bar being to provide the laterally extending ribs or flanges 19, about which may engage the L-shaped flanges 20 of the knife supporting slide. 90 The lower terminal of the marker bar is enlarged to provide a boss or shoulder 21, the upper portion of which forms a stop for the slide and further constitutes a supporting shoulder for the piece of siding when the 95 same is being secured to a building, as will be hereinafter more fully described. Extending laterally from the shoulder 21 is an apertured lug 22 which is adapted to be inserted between the apertured ears or lugs 23 100 extending from the upper terminal of the gage bar 12. A pivot pin indicated at 24 is employed in pivotally securing the member 22 between the members 23.

The gage bar is provided with a flat inner 105 face 25 which is adapted to engage flatly against the last applied piece of siding, as indicated at 26 in Fig. 1 of the drawings.

The lower terminal of the gage bar is directed outwardly and downwardly, as indicated at 27, affording a finger grip by means of which the gage bar may be properly applied when the device is in use. At the junction of the straight portion of the gage bar and the finger piece, there is formed an inwardly extending lug 28 which is adapted to engage against the lower edge of the last applied siding piece, as is also best shown in Fig. 1.

The slide member hereinbefore referred to, consists as best shown in Fig. 5, of a single blank of metal which is bent to form a flat rectangular body portion 29, an upstanding plate 30, and the L-shaped flanges 20. The member 30 rises from the body plate of the slide at one end thereof, so that the knife blade 31 which is shown in Fig. 1 is pivotally attached to the plate by means of the pivot pin 32, may be moved into engagement with the piece of siding or weather-stripping to be marked. A pair of finger plates 33 are carried by the marker bar so that this member may be held against the siding in a convenient manner during the use of the device.

From the foregoing description and upon particular reference to Fig. 1, the manner in which the gage is employed, will be readily appreciated. It will be seen that when a piece of siding is to be marked, the lug 28 is first engaged against the lower edge of the last applied piece of weather-stripping 26 and the hanger bar 10 is then swung inwardly toward the building and secured to it by means of the spike. After the gage is thus secured, the terminal of the piece of siding to be marked is inserted in the space between the inner face of the marker bar and the building, the lower edge of the board being rested upon the shoulder defined by the boss 21, and the members 22 and 23. The piece of siding being thus supported, the slide is moved downwardly from the upper end of the marker bar, the knife having first been swung by its handle 34 to engage its marking point against the piece of siding. After the siding has been marked and subsequently sawed, it may be inserted between the marker bar and the building and supported upon the shoulder 21, while being nailed or otherwise secured.

Projecting laterally from the plate 30 of the knife slide is a stop pin 33 which is positioned to engage the longitudinal stop shoulder 34 of the knife blade for limiting the swinging movement of this member into an operative position.

In reduction to practice, it has been found that the form of this invention illustrated in the drawings, and referred to in the above description as the preferred embodiment, is the most efficient and practical; yet realizing that the conditions concurrent with the

adoption of this device will necessarily vary, it is desirable to emphasize the fact that various minor changes in the details of construction, proportion and arrangement of parts may be resorted to, when required, without sacrificing any of the advantages of this invention, as defined by the appended claims.

What is claimed is:

1. A siding gage including a marker bar, a slide movable longitudinally on the bar, a marker knife pivotally attached to the slide, a hanger bar pivotally carried by the upper terminal of the marker bar, and a gage bar pivotally carried by the lower terminal of the marker bar for movement in a plane at right angles to the wall of the building.

2. A siding gage including a marker bar, a slide movable longitudinally on the bar, a marker knife pivotally attached to the slide, a hanger bar pivotally carried by the upper terminal of the marker bar, a gage bar pivotally carried by the lower terminal of the marker bar for movement in a plane at right angles to the wall of the building, and a laterally extending lug formed on the inner face of the gage bar, said lug being adapted to be engaged against the lower edge of the last applied strip of siding.

3. A siding gage of the character described including a marker bar, lateral longitudinal ribs formed on opposite sides of the bar, a slide movable longitudinally on the marker bar, said slide including a flat body plate engageable against the face of the marker bar, a pair of flanges embracing the edges of the lateral portion of the marker bar, and a plate extending at right angles to the body plate at one edge thereof, a marking knife pivotally attached to the second mentioned plate, a hanger bar pivotally carried by the upper terminal of the marker bar, and a gage bar pivotally depending from the lower terminal of the marker bar.

4. In a siding gage, a marker bar, a knife slide movable longitudinally thereon, a knife pivoted to the slide, a longitudinal stop shoulder formed on the blade of the knife, and a lateral stop pin carried by the slide and engageable with the stop shoulder for limiting the movement of the knife into inoperative position.

5. A siding gage of the character described including a marker bar, said marker bar being substantially T-shaped in cross section for the major portion of its length, and being provided at its lower terminal with a stop shoulder, a channel slide movable on the marker bar, a plate extending at right angles to the slide and from one edge thereof, a marking knife pivoted to said plate, and means for supporting the marker bar in spaced relation to the wall of the building.

6. A siding gage including a marker bar, a hanger bar pivotally connected at the upper terminal thereof, a gage bar pivotally connected at the lower terminal thereof for 5 movement in a plane at right angles to the wall of the building, and a marking knife slidably attached to the marker bar.

In testimony whereof I hereunto affix my signature in the presence of two witnesses.

JOHN WHEELER.
